UNITED STATES PATENT OFFICE.

LOUIS S. BURBANK, OF WORCESTER, MASSACHUSETTS.

MACHINE FOR SEALING CARTONS.

SPECIFICATION forming part of Letters Patent No. 684,788, dated October 22, 1901.

Application filed December 21, 1899. Serial No. 741,071. (No model.)

To all whom it may concern:

Be it known that I, LOUIS S. BURBANK, a citizen of the United States, residing at Worcester, in the county of Worcester and State of Massachusetts, have invented certain new and useful Improvements in Machines for Sealing Cartons; and I do hereby declare the following to be a full, clear, and exact description of the invention, such as will enable others skilled in the art to which it appertains to make and use the same.

In the accompanying drawings, Figure 1 is a side elevation of my machine, partly broken away. Fig. 2 is a plan view of the same. Fig. 3 is a section on the line 3 3, Fig. 1. Fig. 4 is a plan view of the rear end of the machine. Fig. 5 is a section on the line 5 5, Fig. 4. Fig. 6 is a section on the line 6 6, Fig. 5. Fig. 7 is a section on the line 7 7, Fig. 5. Fig. 8 is a section on the line 8 8, Fig. 3, and partly broken away. Fig. 9 is a detail view of a portion of the chain carrier D and the flanges of links thereof. Fig. 10 is a detail view of the finished carton open at one end. Fig. 11 illustrates diagrammatically different steps in the sealing of the carton. Fig. 12 is a detail view, partly broken away, illustrating the operation of the check-piece n. Figs. 13 and 14 are detail views illustrating the devices for rotating shaft w in one direction only. Fig. 15 is a horizontal longitudinal section of the machine, taken below the guide-rods G², parts being removed and the rear end of the machine being broken away.

This invention has relation to machines for sealing the parallel ends of cartons or paper packages; and it consists in the novel construction and combination of parts, as hereinafter explained.

In the accompanying drawings, illustrating the invention, the letter A designates the main framework of the machine, having a track B extending lengthwise thereof for the carrier-links C of the endless-chain carrier D, said links being provided with flanges c, adapted to engage the folded cartons and hold them in proper position as they are carried along, such cartons having the top and bottom flaps

thereof loose and unsealed and presenting 50 laterally of the machine.

The cartons F, for which this machine is chiefly designed, are of rectangular or parallelopiped form, having folding ends, which for better convenience should consist at each 55 end of two pairs of opposite flaps, the outer flaps a a' of one pair folding over the flaps b b of the other pair and at right angles thereto, as indicated. The flaps fold toward the middle of the two ends or top and bottom of the 60 carton, which holds the biscuits or other articles with which it may be charged.

Parallel side walls or plates G are provided at the sides of the trackway and carried by depending arms G', supported from guide-rods G², extending longitudinally upon both sides of the machine, these walls being designed to engage and hold the flaps of the carton in certain positions, as hereinafter described. The flaps b b, which are folded inwardly toward each other, remain in such position throughout the operation of the machine, while the flaps a a', at first folded inwardly toward each other and held in this position by engagement with the side walls 75 or plates aforesaid, are subsequently opened outward for the application of a line or lines of glue or paste and are afterward closed toward each other and upon the flaps b b, to which they are thus glued or pasted at the 80 narrower sides of the top and bottom or ends of the box.

In order to open the flaps a of the carton, an opening or recess g is provided at each side of the machine in the side walls or plates 85 G, said opening or recess extending vertically and the side walls G and the side walls of such recesses being extended at each side of such opening or recess to form laterally-projecting corners g' g''. As the carton is 90 carried along in engagement with side walls or plates G its flaps a, through their inherent elasticity, will when the openings g are reached partly open, when the rear flaps a will be engaged by projecting corners g'' and 95 spread and held completely open as the flaps pass into engagement with the subsequent portions of the side walls or plates. In a

somewhat similar manner the forward flaps a' are spread and held open. As the carton escapes from engagement with the first sections of the side walls or plates openings h between such first plate-sections G and subsequent sections G^x allow these flaps to partly open automatically, when they are immediately engaged by spreading-slide h' , having a rapid forward-and-back movement or reciprocation and serving to turn these flaps completely outward in time for them to pass in full-open position into engagement with the next sections of the side walls or plates G^x . The flaps a a' of the carton are now both 15 fully open in position for the application of lines of glue near their upper and lower edges, such gluing being effected by the disks f , which are fed from glue-pans f' . By means of a subsequent set of openings or recesses g and h in the side walls or plates G^x and similar to those already described as serving to spread the flaps a a' open these flaps after the application of the glue are closed upon the flaps b , the forward flaps a' 20 being closed by projecting corners g'' of second openings g , and a second closing-slide h' , having rapid forward-and-back motion or reciprocation, serving in this operation to close the rear flaps a . These slides h h' are 25 carried by depending arms h^3 of transverse arms h^4 , supported and sliding upon guide-rods G^2 aforesaid. These transverse arms h^4 are connected together by longitudinal rods G^3 , forming the slide-frame H , which is operated 30 by levers H' , intermediately connected by transverse rods H^2 and operated by eccentric H^3 , carried by shafts H^4 , in gear with the power or sprocket shaft. An eccentric rod and strap H^5 connect rods H^2 with eccentric 35 H^3 . The upper ends of said levers H' are connected to cross-pieces h^5 , located between the pairs of transverse arms h^4 and having a connection with rods G^3 to move the same, and hence the slide-frame H . 40

45 The flaps of the ends of the cartons having been folded and glued are ready for the application of a sealing strip or ribbon along the central vertically-arranged seam where the flaps a a' come together. For this purpose a reciprocating frame K is provided, moving upon the slideway L of the main frame and carrying the sealing-ribbons of reels R and the devices for operating and clipping the same. The frame K is operated 50 to move at the same rate of speed as the endless-chain carrier D by means of the eccentrics at k upon shaft H^4 having a gear connection H^6 with the power-shaft, such eccentrics having a rod-and-strap connection k' 55 with levers K' , in turn connected to frame K . The frame K is therefore designed to move with each carton a distance sufficient for its mechanism, hereinafter described, to place the sealing-strips thereon, such frame 60 having for this purpose a short regular reciprocatting movement.

L' represents a stationary frame located

centrally of the slideway-frame L and projecting upwardly through a central opening in the base of the frame K . This frame L' 70 has a suitable slideway i for a short rack I , designed when the finger J is raised by the passage of the carton thereunder to lock the rack in stationary position and rotate reciprocating pinion p , having bearings in slide-frame K , and thereby through the medium 75 of the worm and worm-wheel gearing w' to turn the shafts w inwardly and operate the ribbon-moving mechanism. On the backward movement of slide K the finger J will 80 have escaped from engagement with the carton and is returned to normal position through gravity and spring-slide s , and the rack I being no longer locked stationary will not actuate the pinion p . Should one of the carrying-links of the conveyer-chain be empty, 85 the finger J will not be raised and the ribbon-moving mechanism will not be set in operation through such rack and pinion. This automatic operation is effected by the employment of a pin or check-piece n , Fig. 12, 90 adapted to engage the forward end of the rack I to hold the same stationary, such pin n being engaged by section s' , having an inclined wall engaging an inclined wall of slide 95 s and operating upon forward movement of slide s to raise section s' and check-piece n therethrough. Slide s is moved in one direction by operation of the finger J aforesaid and returned to normal position by spring s^2 100 thereof when said finger falls. When the pin n falls, its engagement with the rack ceases and the latter being of little weight reciprocates freely in its slideway with the pinion and without turning the same. The 105 pinion p is moved back to normal position with relation to its rack I , while the rack is held stationary and the slide-frame K is returned to normal position, there being a frictional engagement of the upper surface of 110 check-piece n with the lower surface of the rack for this purpose.

For the purpose of rotating the shafts w in one direction only friction-wheels W are provided, (see Figs. 13 and 14,) mounted upon the 115 shafts P of pinions p and having a driving connection at w^x with the spiral gears w' . Within these wheels W are the clutch devices W' , having friction-shoes w^2 , arranged to engage the inner peripheral surfaces of such 120 wheels. These shoes are pivoted to arms of bell-crank levers W^3 , in turn pivoted to clutch-hubs w^3 , having a driving connection at w^4 with shafts P . Springs w^5 engage the other arms of said bell-crank levers and are arranged to throw such shoes out of frictional 125 engagement with such wheels during rotation of spiral gears w' in one direction. When such gears are rotated in the opposite direction, the inner peripheral surfaces of wheels 130 W take a bearing against such shoes to force a frictional engagement therebetween and turn shafts w .

Cross-arms Q , connected to an elevated por-

tion K^3 of frame K , have tracks q for the axis piece or shaft q' of ribbon-reels R , which rotate from above inwardly, the inner edge of the rolls moving against a guide piece or abutment r , preferably of wood, which guides the descending strip of ribbon between the gluing-rollers V and V' . A longitudinal V -form bend is made in the ribbon or strip as it passes between the rollers V and V' , whose peripheries have respective engaging convex ribs and concave grooves v and v' . The co-action of these concave and convex grooves and ribs upon the ribbon forms the longitudinal V -form bend or crease, which gives the strip proper stiffness for the downward feed. The glue is taken up from the glue-pan P by the inner rollers V' . Levers M , having a fulcrum at m upon slide k , from which they depend, are designed to operate the ribbon pressing and clipping devices.

Y represents spring pressure-plates carried by said levers M at their lower end portions and presenting inwardly toward the carton-flaps and the sealing-strip upon the meeting edges of said flaps. Such plates Y upon actuation of levers M are pressed inwardly upon the flaps of the carton, flattening the sealing-ribbon against the approximated edge portions of the flaps a and a' with a yielding pressure. At the same time the slide-knives z , carried by slide-frames Z , having movement in suitable guideways, are moved inwardly through link connection j' with such levers to cut the ribbon at the top of the carton. The reverse motion of levers M releases the pressure of the plates Y and the sealed carton is carried forwardly upon the link conveyer between the traveling pressure-walls x of the drying-chambers X , which are charged with air of proper temperature to facilitate setting and drying the glue or paste employed in sealing the carton. The inner or pressure walls of the pneumatic chambers are endless belts of leather or other suitable yielding material. Levers M are operated by eccentric M' upon shaft H^4 , having an eccentric rod and strap connection m' with arm m^2 of rock-shaft m^3 . Arms m^4 of such rock-shaft are connected at m^5 to such levers.

Having thus described my invention, what I claim, and desire to secure by Letters Patent, is—

1. In a sealing-machine for cartons or paper boxes having foldable flaps, the combination with an endless-chain carrier, and the carton-flap engaging side walls provided with openings therein, of means adjacent to such

openings for opening and closing such flaps, substantially as specified.

2. In a sealing-machine for cartons or paper boxes having foldable flaps, the combination with an endless carrier, and the carton-flap-engaging side walls provided with successive openings therein, of stationary means adjacent to a portion of such openings, and reciprocating means adjacent to the remainder of such openings, for opening and closing such flaps, substantially as specified. 60

3. In a sealing-machine for cartons or paper boxes having foldable flaps, the combination with the endless carrier, of the reciprocating frame, the ribbon-reel carried by said frame, and means also carried by said frame for applying and securing the ribbon to the approximated edges of said carton-flaps, substantially as specified. 70

4. In a sealing-machine for cartons or paper boxes having foldable flaps, the combination with the endless carrier, of the reciprocating frame, the ribbon-reel carried by said frame, and the ribbon feeding, gluing, cutting, and pressing devices also carried by said frame, substantially as specified. 80

5. In a sealing-machine for cartons or paper boxes having foldable flaps, the combination with the endless box-carrier, and means for driving the same, of the lateral flap-sealing devices, the reciprocating ribbon applying, sealing, and clipping mechanism, and the drying-chambers, substantially as specified. 85

6. In a sealing-machine for cartons or paper boxes having foldable flaps, the combination with the endless box-carrier, the reciprocating frame and the ribbon feeding and applying devices in connection therewith, of driving mechanism for such feeding and applying devices, and an automatic latch adapted to set such mechanism in action only when engaged by a box or carton upon the carrier, substantially as specified. 90

7. In a machine for sealing cartons or paper boxes, the endless box-carrier, the reciprocating frame, carrying means for sealing such boxes, and means operated by the passage of the box to set such first-named means in operation to seal the boxes, substantially as specified. 100

In testimony whereof I affix my signature in presence of two witnesses.

LOUIS S. BURBANK.
